(57) **CLAIM**

The ornamental design for a dryer for histological preparation, as shown and described.

DESCRIPTION

FIG. 1 is a left-top-front perspective view of a dryer for histological preparation, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

Broken lines are included for purpose of illustrating portions of the dryer for histological preparation that form no part of the claimed design.

1 Claim, 7 Drawing Sheets
